STEAM GENERATING UNIT HAVING A SUPER-HEATER AND REHEATER EACH INCLUDING A RADIANT SECTION AND A CONVECTION SECTION

Paul H. Koch, Bernardsville, William D. Stevens, Hackensack, and Murray Wiener, Newark, N.J., assignors to The Babcock & Wilcox Company, New York, N.Y., a corporation of New Jersey

Filed May 10, 1955, Ser. No. 507,438

7 Claims. (Cl. 122—481)

This invention relates to the art of steam generation. It is more particularly concerned with steam generation, superheating and reheating at high temperatures and high pressures. The steam pressures are within the range of 1500 to 3000 p.s.i.a., and the steam superheat and reheat temperatures are within the range of 1000° F. to 1200° F.

The invention is also concerned with the generation, superheating and reheating of high pressure steam in a steam generating unit of high capacity, within the range of 500,000 to 2,000,000 pounds of steam per hour, the unit being fired by a fuel burning means providing combustion gases at a maximum temperature within the range of 2400° F. to 3300° F.

In one of its aspects, the invention is characterized by the passage of high temperature combustion gases to a radiant heat absorption zone, which may be exemplified by a large volume furnace chamber in which the walls of the chamber are lined with closely arranged tubes, at least some of which constitute a radiant superheater or reheater. Within a part of the radiant heat chamber more remote from the fuel burning means, there are widely spaced platens or curtain walls, each consisting of closely arranged radiantly heated steam heating tubes. Preferably, these spaced platens or curtain walls are alternatively secondary steam superheater platens and steam reheat platens.

At the gas outlet of the radiant heat chamber of the unit, the gases enter a convection section which is divided into two parallel gas passes, with one of these gas passes having wholly convection steam reheat surface therein and the other gas pass having wholly steam superheating surface therein. Preferably, both the steam reheat and the secondary superheater are so constructed and arranged that each includes a substantial proportion of the predominantly radiantly heated surface in the radiant heat absorption chamber and a substantial proportion of the convection heated surfaces within the convection section. Such inclusion of both the radiantly heated surfaces and the convection heated surfaces in the reheat and in the superheater promotes the attainment of a predetermined steam temperature over a wide range of rate of vapor generation, because of the opposing inherent tendencies of the predominantly radiantly heated sections and the predominantly convection heated sections, as the rate of vapor generation changes. With this type of arrangement also the ratio of predominantly radiantly heated surface to predominantly convection heated surface in the reheat may be greater than the corresponding ratio in the superheater, so as to compensate for the tendency of the reheat to have a greater loss in steam temperature than the temperature loss of the superheater, as the rate of vapor generation decreases.

The invention also involves a type of wall construction for the radiant heat zone provided by a secondary furnace chamber, this wall construction involving two rows of heat absorbing tubes within a pressure tight casing con-

2

struction. In this type wall construction the tubes immediately inward of the pressure tight casing are vapor generating wall tubes or risers, and spaced inwardly of and structurally tied to these tubes are the closely arranged tubes of a wall tube steam superheater. The superheater tubes are tied together in wall forming alignment so as to maintain the integrity of the wall tube superheater, and the wall tube superheater, as an entity, is preferably tied to the risers or steam generating tubes so that there may be relative movement between the two different types of wall tubes.

The invention is also regarded as involving the method of attaining superheat and reheat control over a wide range of rate of steam generation, effected by the illustrative unit. The method involves the passage of steam to be superheated through a zone which is predominantly convection heated and then through a zone which is predominantly radiantly heated. The method also involves a similar type of procedure for the convection and the radiant steam reheating. It may also involve interspersing of the predominantly radiantly heated zones for reheating, relative to the predominantly radiantly heated zones for steam superheating.

The steam generating, superheating and reheating unit of the invention also involves, in combination with the arrangement above indicated, the disposition of at least some of the reheat surface ahead of the superheater surface, with respect to gas flow.

The invention will be concisely as set forth in the 30 claims appended hereto, but for a complete understanding of the invention, its uses and advantages, recourse should be had to the following description which refers to the accompanying drawings in which a preferred embodiment of the invention is illustrated.

35 In the drawings:

Fig. 1 is a partly diagrammatic sectional side elevation of a cyclone furnace fired steam generating, superheating and reheating unit, embodying the invention;

Fig. 2 is a sectional plan taken on the line 2—2 of 40 Fig. 1;

Fig. 3 is a fragmentary vertical section showing a relative arrangement of the roof tubes of the secondary furnace chamber and the headers for the widely spaced platens or curtain walls of steam heating tubes pendently arranged within the upper part of the secondary furnace 45 chamber, this view being taken on the line 3—3 in Fig. 2;

Fig. 4 is a fragmentary horizontal section at a position such as that indicated by the line 4—4 of Fig. 1, and showing the arrangement of the riser tubes, the exterior 50 gas tight casing arranged along the outer sides of these tubes, and the row of closely spaced steam superheater tubes which are tied to the larger diameter risers;

Fig. 5 is a fragmentary side elevation of the Fig. 4 structure, on the line 5—5 of Fig. 4;

Fig. 6 is a fragmentary horizontal section of a modified double wall tube wall construction taken on the line 6—6 of Fig. 7;

Fig. 7 is a fragmentary side elevation of the Fig. 6 structure taken on the line 7—7 of Fig. 6;

Fig. 8 is a cut-away perspective view showing a fragmentary part of another embodiment of the double tube row furnace wall construction somewhat similar to the embodiments indicated in Figs. 4 and 6; and

Fig. 9 is a plan view on a smaller scale of the wall 65 construction illustrated in Fig. 8.

Fig. 1 of the drawings diagrammatically illustrates a natural circulation steam generating unit having a steam and water drum 10 having therein drum internals, including steam and water separating devices 11 such as those illustrated by the patent to Fletcher and Rowand 2,289,-970. From the water space of this drum water flows

downwardly through large diameter downcomers 12 to a lower drum 14 at the lower part of the unit. Leading upwardly from the drum 14 are a plurality of rows of steam generating furnace wall tubes, the intermediate parts of which delineate the boundaries of the radiant heat absorption zone formed by the secondary furnace chamber 16. This chamber is of such large dimensions, in a high capacity unit, that it may be of a height of the order of 75 feet, of a width of the order of 60 feet between the side walls which connect the front wall 18 and the rear wall 20. These side walls may have a depth of the order of 20-30 feet.

The system of steam generating furnace wall tubes of the Fig. 1 unit includes, at the lower part of the unit, the wall tubes 22 which are connected at their upper ends to the intermediate header 24. From the upper part of this header the wall tubes 26 lead along the upper part of the wall 20 to the upper wall tube header 28, which is appropriately connected to the drum 10. Other wall tubes 30 lead from the drum 14 along the floor 32 of the primary furnace chamber 34, then along the wall components 36-38 which separate the cyclone furnaces 40 and 42 from a common primary furnace chamber 34. These cyclone furnaces are preferably of a type illustrated in the U.S. patent to Kerr et al. 2,594,312. They preferably burn a particle form slag forming fuel such as granulated coal and have re-entrant throats such as 44 and 46 through which combustion gases at temperatures within the range of 2400° F. to 3300° F. pass into the primary furnace 34. At the lower part of each cyclone furnace chamber, and at positions such as those indicated at 48 and 50, fused incombustible such as slag, flows through appropriate openings in the wall components 37 and 36 into the primary furnace chamber 34, collects upon the floor 32, and exits through an opening 33 in that floor.

Parts of the steam generating tubes in the wall components 36-38 separating the cyclone furnaces from the primary furnace chamber 34 are included in the constructions providing the cyclone furnace throats 44 and 46. The next superjacent parts 50 of these tubes extend along the inclined front wall section 52 to the vertical section of the wall 18 where they continue as the vertical sections 54 to connection with the drum 10, as indicated at 56.

Intermediate the wall tube sections 22 extending along the lower part of the furnace wall 20, and the wall tube portions between the cyclone furnaces and the primary chamber 34 are other steam generating tubes, the lower parts of which are indicated at 60. From these lower parts these tubes continue upwardly in widely spaced screen portions 62 and 64. Above this screen these tubes continue in wall alignment to form the basis for the refractory covered wall 66 dividing the primary chamber 34 from the lower part of the secondary furnace chamber. Above the upright wall 66 these tubes continue through the inclined parts 68 forming the basis for the refractory lined roof of the primary furnace chamber 34. They then continue along the inclined wall section 52, and between the wall tubes 54 along the vertical front wall 18. They continue upwardly along that wall to such connections with the drum 10 as those indicated at 56. A similar arrangement of steam generating furnace wall tubes is included in the side walls of the furnace chamber, connecting the front wall 18 with the rear wall 20, and such systems of side wall tubes are appropriately connected by means of upper headers and lower headers, and other appropriate tubular connections to the drum 10 and the lower drum 14.

Combustion gases with some particles of fused combustible suspended therein pass from the cyclone furnaces into the primary furnace chamber at temperatures within the range of 2300° F. to 3300° F. Some of the suspended particles of fused incombustible are deposited from the gases within the primary furnace chamber to

collect in the pool of slag 35 along the refractory covered slag tap bottom 32. The temperature of the gases is lowered somewhat by the heat absorption of the steam generating tubes forming the walls of the primary furnace chamber. The gases then pass between the screen tubes 62 and 64 into the lower part of the secondary furnace chamber 16. This part of the secondary furnace chamber, as indicated in Fig. 1, has all of its walls including upright steam generating tubes having a multiplicity of metallic studs welded thereto for holding a high temperature refractory covering which lines the lower part of the secondary furnace chamber.

Upwardly from the level of the header 24 all of the walls of the secondary furnace chamber 16, with the exception of the inclined wall 52, are lined with tangent or closely arranged radiant superheater tubes which will be later referred to. Some of these tubes are indicated at 70 in Fig. 2 as disposed along the side wall portion 72, the opposite side wall portion 74 having similar radiant superheater tubes 76 disposed therealong. The radiant superheater tubes disposed along the wall 20 are indicated at 78 in Fig. 1, and the radiant superheater tubes disposed along the front wall 18 are indicated at 80 in Fig. 1 and Fig. 2.

As the gases pass upwardly through the radiant heat absorption zone immediately above the level of the header 24, the temperature is substantially decreased by the radiant heat transmission therefrom to the radiant superheater wall tubes, and above an intermediate position designated as A-B in Fig. 1 radiant heat is absorbed from the gases at a much higher rate because of the addition to the radiant superheater tubes along the walls of the secondary combustion chamber 16 of a number of reheat and secondary superheater platens disposed in parallelism with the side wall portions 72 and 74, and widely spaced (i.e. 6 feet) across the 60-foot dimension of the secondary furnace chamber. Some of these platens are reheat platens as indicated at 82, 84, 86, 88 and 90 in Fig. 2, and the intervening platens as indicated at 83, 85, 87 and 89 are secondary superheater platens. Each platen preferably consists of pendent U-tubes having downflow legs such as those indicated at 90A in Fig. 3 leading downwardly from a reheat header 90B, and an upflow leg, the main part of which is in wall tube alignment with the downflow leg. The uppermost part of such an upflow leg is indicated at 90C in Fig. 3 as discharging into the header 90D. The headers 90B and 90D are supported from appropriate structural steelwork by suitable hangers which are generally indicated at 90E in Fig. 3. The superheater platen tubes are similarly constructed and have similar arrangement of headers and tubes for each platen, with the exception of the superheater secondary furnace wall tube platens immediately adjacent the upright steam generating wall tubes of the secondary furnace chamber, as indicated in the right hand part of Fig. 3. Here the steam generating tubes of the side wall are indicated at 92 as connected to a header 94 supported from steelwork by appropriate hangers 96. The U-tubes for the radiant superheater along the secondary furnace chamber wall adjacent the tubes 92 are indicated at 70. Each U-tube may be considered as having an inlet leg 70A leading from the inlet header 70B, and an outlet leg 70C leading to the outlet header 70D.

The roof of the secondary furnace chamber 16 also includes secondary superheater tubes 100 constituting continuations of the front wall radiant superheater tubes 80, and serving with these tubes to conduct steam from the secondary superheater inlet header 102 to the intermediate secondary superheater header 104.

The walls of the cyclone furnaces 40 and 42 include vapor generating tubes appropriately connected into the natural circulation of the unit by means of suitable headers and connecting tubes. One of such headers is shown at 106 in Fig. 1. From this header risers 108 lead upwardly and then through the inclined wall 52 in platen

formation with the tubes in closely arranged or contiguous relationship to form the platens 110—114 as indicated in Fig. 2. These narrower platens are preferably aligned with the reheat platens 82, 84, 86, 88 and 90. The upper ends of these platens are suitably connected by appropriate headers and circulators to the drum 10. The lower ends of the platen tubes may be in communication by suitable connections with the lower drum 14.

The combustion gases passing upwardly within the secondary furnace chamber 16 continue past the level A—B and into the zone of the secondary superheater and reheat platens with a small proportion of the particles of fused incombustible still suspended therein, but the increased rate of radiant heat transfer from the gases and their suspended slag particles to the tubes of the reheat and secondary superheater platens soon reduces the temperature of the gases to values at which the suspended particles will not stick to and accumulate upon the more closely spaced superheater and reheat tubes.

The convection section of the unit is illustrated in Fig. 1 as including a horizontal gas pass leading laterally to the right from the upper end of the secondary furnace chamber 16. As indicated in Fig. 2 this convection section is divided in the direction of flow of the gases into a reheat gas pass 110 and a superheater gas pass 112 by an upright wall 114A. The heating surfaces within the gas pass 110 are wholly formed by reheat elements and the convection sections within the gas pass 112 are wholly superheater elements. At the high temperature or leading part of the gas pass 112 there is the convection superheater section 116 from which the gases continue across the elements of the primary superheater section 118.

From the outlets of the gas passes 110 and 112 the gases turn downwardly for flow through a gas pass 120 in which there are disposed the convection economizer sections 122 and 124.

Steam flows from the steam space of the drum 10 through a number of lines directed as indicated at 126. Some of these lines have the vertically arranged downflow sections 128 leading to an appropriate inlet header, paired with an adjacent outlet header, both of the headers extending along one side wall of the convection gas pass. Connecting these headers are U-tubes, the downflow and upflow legs of which form wall tubes along a side wall of the gas pass of the convection section, the arrangement of these headers and their connected superheater wall tubes being similar to the arrangement of headers and U-tubes indicated in Fig. 3 for the reheat and superheater platens at the upper portion of the secondary furnace chamber. From the outlet header, paired with the inlet header 130, the steam flow continues through the outlet connections 132 to an intermediate primary superheater header 134.

Others of the steam supply lines 126 leading from the drum 10 have the downflow legs 136 leading to a primary superheater inlet header 138, from which steam flows through a plurality of closely arranged roof tubes 140 along the roof of the gas passes of the convection section. The steam flow through these roof tube sections continues through the upright tube sections 142 at the rear of the convection gas passes, and then through the superheater sections 144 across the entrance to the downflow pass 120. Thence the steam flow continues through the tubular sections 146 and 148 along the floor sections 150 and 152 of the convection gas passes. These steam flow tubes continue downwardly along the rear furnace wall 20 and inwardly of the riser tubes 26 through the downflow legs 78 of U-tubes to a level adjacent the header 24, whence the steam flow reverses and continues through the upflow legs 160. Across the gas inlet of the convection section these upflow legs 160 are more widely spaced as indicated at 162 and 164 to form a screen across the gas flow from the upper part of the secondary furnace

chamber to the convection gas passes. The steam flows from these tubes continue to the intermediate header 166 of the primary superheater. From this header the steam flows continue through the lines 168 to the mixing header 134 of the primary superheater.

Described above is one steam flow circuit through tubes along one side wall of the convection gas pass, with the steam flow emerging from this circuit into the mixing header 134. It is to be understood, however, that there is another series of steam flow circuits for the opposite exterior wall of the convection gas pass, with the steam flows of those circuits also emerging into the mixing header 134. Thus there are three parallel flows of steam in the primary superheater with the steam from each flow reaching the mixing header 134 before entering the convection section 118 of the primary superheater. This convection section consists of a plurality of platens each having multiple looped and series connected U-tubes receiving steam through one of a multiplicity of inlets 170, 20 and ultimately discharging the steam through one of a plurality of outlets 172 into the primary superheater outlet header 174.

From the header 174 the steam flow continues through a plurality of lines 176 through a spray attemperator 178, 25 and then through a corresponding number of lines 180 to the inlet header 102 of the secondary superheater. From this header the steam flows through the inlet legs of continuous U-tubes constituting the roof tubes 100 of the secondary furnace chamber, and the furnace wall tubes 80. 30 From the outlet legs of these U-tubes the steam flows through the secondary superheater intermediate header 104 and thence through connections 184 leading in parallel to the inlet headers for the secondary superheater platens in the upper part of the secondary furnace chamber. 35 One of such headers is indicated at 70B in Fig. 3.

From the outlet headers of the secondary superheater platens or curtain walls in the upper part of the secondary furnace chamber, such as the header 70D of Fig. 3, the steam flows in parallel through one or more lines 186 40 to the inlet header 188 of the secondary superheater convection section 116. This secondary superheater section is illustrated as consisting of a plurality of series connected U-tubes conducting steam to the header 190, from which the steam flows to a turbine, or other point of use.

45 Relative to the secondary superheater there has been described above one flow circuit leading from the inlet header 102 through the roof tubes 100, and then through the furnace front wall secondary superheater tubes 80 and back to the secondary superheater intermediate header 104. There are also two other circuits connected in parallel with this circuit. One of these additional circuits includes appropriate lines leading from the header 102 to such headers as the header 70B which is indicated in Fig. 3 as the inlet header of one of the furnace side wall 50 secondary superheater radiant sections. In this furnace wall radiant superheater section the steam flows through the downflow legs of the U-tubes, and then through the adjacent upflow legs to the outlet sections 70C to the header 70D, and thence through appropriate lines to the 55 secondary superheater intermediate header 104. The second additional parallel circuit for the secondary superheater between the headers 102 and 104 consists of an arrangement of tubes and headers similar to those indicated in Fig. 3 for the furnace side wall opposite the wall 60 along which the steam generating tubes 92 are disposed. Thus there are three parallel circuits for the secondary furnace chamber wall tube radiant superheaters leading from the inlet header 102 to the intermediate header 104.

The reheat has appropriate headers and tubular connections through which steam flows from the outlet of one stage of a steam turbine to the inlet headers for the reheat platens at the top of the secondary furnace chamber. One of such inlet headers for the reheat platens is indicated at 90B in Fig. 3. Steam flows in parallel to 75 all of the headers 90B for the various reheat platens

and then downwardly through the downflow legs of the U-tubes of the platens, then through the upflow legs to the outlet headers for the reheater platens, one of such headers being indicated at 90D in Fig. 3. Steam flows in parallel from the outlet reheater platen headers 90D through appropriate connections to a spray attemperator and thence through an inlet header for the convection section of the reheater disposed within the reheater gas pass 110. This reheater inlet header is aligned with the mixing header 134 for the primary superheater, and the steam to be reheated flows from this header through series connected U-tubes constituting successive banks of tubes, similar to the banks of tubes of the primary superheater section 118. Such banks of tubes, or sections of the convection section of the reheater, are indicated at 200—204 in the upper part of Fig. 2. The outlet header for the convection section of the reheater is axially aligned with the header 190 for the convection section 116 of the secondary superheater, as indicated in Fig. 1 of the drawings.

The different wall tube constructions indicated in Figs. 4—9 of the drawings are of types which may be used in a double wall construction for the secondary furnace chamber 16 of the Fig. 1 unit.

Each wall tube arrangement includes a row of relatively large diameter riser tubes disposed in wall alignment exteriorly of a row of smaller diameter radiant superheater tubes also secured in wall alignment. In the arrangement indicated in Figs. 4 and 5 riser tubes 26 are welded as indicated at 220 and 222, to a buckstay 224. Such buckstays are vertically spaced and between the buckstays at successive elevations there are panels 226, outwardly flanged as indicated at 228, and having seal welds 230 uniting the edges of the flanges with the contiguous edges of the flanges 232 of the buckstays. A pressure tight casing is completed by similar seal welds, some of them joining horizontally adjacent panels.

The radiant superheater tubes 78 and 160 are held in wall alignment by rods or pins 240 extending through aligned sleeves 242—244 and held in position by a tack weld to one of these sleeves. Two of the sleeves, such as 242 and 244, for example, may be welded to the tube 160 and the intermediate sleeve 243 welded to the adjoining tube 78. Means for tying the tubes together may be used in such a manner that a group of four tubes is thus tied together, whereas the tubes of the next succeeding group of four tubes are tied separately together.

The wall of superheater tubes in the arrangement of Figs. 4 and 5 is held in spaced relationship to the wall of riser tubes 26 by tying means which permit relative movements of the different tube walls. This means consists in T-lugs 250 welded to the tubes 78 and 160 as shown, with the head of the T of each lug embraced by the converging lateral extensions 252 and 254 of the companion lugs 256 and 258 welded to the tube 26 immediately to the rear of the tube 78, to which the member 250 is welded. Such tying means are preferably distributed horizontally and vertically over the face of the radiant superheater wall so that it may be maintained in operative relationship to the wall of riser tubes, while permitting a limited relative movement of the walls formed by the two different tubes.

In the wall construction indicated in Figs. 6 and 7, arrangement of the buckstays and the panels welded thereto is much the same as that described with reference to the construction shown in Figs. 4 and 5. Also, the manner in which the wall superheater tubes are secured in operative relationship to the wall of riser tubes 260 is the same as that indicated in Figs. 4 and 5.

The wall construction of Figs. 6 and 7, however, includes refractory material 270 preferably installed as a plastic or semi-plastic between the wall of superheater tubes and a web of reticulated metal 272 secured to and extending between adjacent tubes 260. The Fig. 6 and Fig. 7 arrangements also include the rods 274 disposed

in the grooves formed by the substantially contiguous adjacent tubes and welded to the adjacent tubes as indicated at 275.

In the furnace wall construction of Figs. 8 and 9, the closely arranged tubes 280 of the radiant superheater furnace wall may be secured in their wall alignment in the manner indicated in Figs. 4 and 6, or the radiant superheater tubes may be held in their wall alignment by securement to the superheater buckstay 282. This buckstay is a part of a gas-tight wall including panels such as 284 and 286 having circumscribing seal welds securing the panels together at the outer edges of their flanges, and having the edges of some of the panels welded directly to the edge portions of the buckstays, such as 282, all in a manner previously indicated with reference to the type of wall construction indicated in Figs. 4 and 5.

The larger diameter riser tubes 288 of the Fig. 8 construction may lead upwardly from a header such as the header 24 of Fig. 1. In this case, the curved casing component 290 extends inwardly and upwardly from the header to junction with a channel expansion joint construction 292, the upper flange 294 of which is disposed adjacent the outer edge portion of the flange 296 of the buckstay 282, and is seal welded thereto to act as a part of the casing construction and to permit relative movement between the superheater tubes 280 and the tubes 288, and the header to which they are secured.

The row of risers 288 of the Fig. 8 and Fig. 9 constructions is spaced substantially outwardly of the row of radiant superheater tubes 280, and both rows of tubes 30 are held in their operative relationship by guides or connectors 298 and 300 which engages the flanges 302 and 304 of the buckstay 306 to hold the rows of tubes in their operative relation to the buckstay. The connectors 298 include plates such as 308 secured to the tubes 288 by welding and having upper and lower angular lugs 310 and 312 slidably engaging the inner surfaces of the buckstay flanges 302 and 304.

The connector devices 300 for the radiant superheater wall including the buckstay 282 and the tubes 280 also involve a number of longer plates such as those indicated at 314. The inner ends of these plates are disposed within the channel of the buckstay 282 and are welded thereto as indicated at 316, while the outer ends of the plate members 314 have the angular lugs 318 and 320 welded thereto so as to slidably engage the flanges 302 and 304 of the buckstay 306.

Although the invention has been described with particular reference to the details of a preferred embodiment, it is to be appreciated that the invention is not necessarily limited to all of the details thereof. It is rather to be considered as of a scope commensurate with the scope of the subjoined claims.

What is claimed is:

1. In a steam generating unit having a section including steam generating wall tubes, fuel burning means associated with the steam generating section for developing high temperature combustion gases from which heat is radiantly transmitted to the steam generating wall tubes, steam superheating wall tubes defining a large volume radiant heat absorption zone of a furnace chamber receiving the high temperature gases, a convection section including an arrangement of walls forming a convection gas pass communicating with gas flow from the furnace chamber, a superheater having a convection section disposed within the convection gas pass, the superheater also having a radiant section including widely spaced platens of tubes disposed at a position ahead of the entrance of the convection gas pass, and a reheater having a convection section within a convection gas pass communicating with gas flow from the furnace chamber and also having widely spaced radiant platens of tubes disposed in a zone of high temperature gases ahead of the gas entrance of the convection gas pass and intermediate and spaced from said superheater platens, a part

of the steam superheating wall tubes being disposed ahead of the re heater platens relative to gas flow.

2. In a steam generating unit, upright steam generating tubes disposed along the walls of a vertically elongated secondary furnace chamber, parts of said tubes also defining the boundaries of a primary furnace chamber at the bottom of a unit, a cyclone furnace burning fuel at temperatures within the range of 2400° F.-3300° F. and delivering high temperature combustion gases to the primary furnace chamber for subsequent flow into and upwardly through the secondary furnace chamber, wall means defining a convection gas pass leading from the upper part of the secondary furnace chamber, a superheater having closely arranged furnace wall tubes lining a wall of the secondary furnace chamber, wall means dividing the gas pass into two parallel gas passes, the superheater also having a convection section disposed within one of said parallel gas passes, a re heater having a convection section disposed within the other of said convection gas passes and having a predominantly radiantly heated section including widely spaced platens of closely arranged re heater tubes disposed within the upper part of the secondary furnace chamber and ahead of the gas entrance of the convection gas pass, means providing a flow of steam to be superheated first through said wall tubes and then through said convection section, and means providing a flow of steam to be reheated first through said platens and then through said re heater convection section.

3. A steam generating, superheating and reheating unit comprising walls defining a vertically elongated furnace chamber having fuel burning means providing high temperature heating gases at its lower end and a convection heating gas pass extending laterally from its upper end, a vertical baffle longitudinally dividing said gas pass into two side-by-side passages, a convection secondary steam superheater positioned in one of said passages adjacent said furnace chamber, a convection primary steam superheater positioned in said passage rearwardly of said secondary superheater, a convection steam re heater in the other passage, radiant steam superheating tubes extending along one of the walls of said furnace chamber, a plurality of groups of steam superheating tubes arranged in widely spaced vertical platens in the upper part of said furnace chamber and positioned intermediate and spaced from said superheater platens, means providing a flow of steam to be superheated serially through said furnace chamber wall superheater tubes, convection primary steam superheater, superheater tube platens, and convection secondary superheater, and means providing a flow of steam to be reheated serially through said re heater tube platens and then through said convection steam re heater.

4. A steam generating, superheating and reheating unit comprising front, rear and side walls defining a vertically elongated furnace chamber having fuel burning means providing high temperature heating gases at its lower end and a convection heating gas pass extending laterally from its upper end, a vertical baffle longitudinally dividing said gas pass into two side-by-side passages, a convection secondary steam superheater positioned in one of said passages adjacent said furnace chamber, a convection primary steam superheater positioned in said passage rearwardly of said secondary superheater, a convection steam re heater in the other passage, steam superheating tubes extending along the roof and floor of said heating gas pass, a plurality of groups of steam superheating tubes arranged in widely spaced vertical platens in the upper part of said furnace chamber, a plurality of groups of steam reheating tubes arranged in widely spaced vertical platens in the upper part of said furnace chamber and positioned intermediate and spaced from said superheater platens, means providing a flow of steam

to be superheated serially through said convection pass roof and floor superheater tubes, convection primary steam superheater, superheater tube platens, and convection secondary superheater, and means providing a flow of steam to be reheated serially through said re heater tube platens and then through said convection steam re heater.

5. A steam generating, superheating and reheating unit comprising front, rear and side walls defining a vertically elongated furnace chamber having fuel burning means providing high temperature heating gases at its lower end and a convection heating gas pass extending laterally from its upper end, a vertical baffle longitudinally dividing said gas pass into two side-by-side passages, a convection secondary steam superheater positioned in one of said passages adjacent said furnace chamber, a convection primary steam superheater positioned in said passage rearwardly of said secondary superheater, a convection steam re heater in the other passage, steam superheating tubes extending along the roof and floor of said heating gas pass, radiant steam superheating tubes extending along the walls of said furnace chamber, a plurality of groups of steam superheating tubes arranged in widely spaced vertical platens in the upper part of said furnace chamber, a plurality of groups of steam reheating tubes arranged in widely spaced vertical platens in the upper part of said furnace chamber and positioned intermediate and spaced from said superheater platens, means providing a flow of steam to be superheated serially through said convection pass roof and floor superheater tubes, furnace chamber rear wall superheater tubes, convection primary steam superheater, front and side wall superheater tubes, superheater tube platens, and convection secondary superheater, and means providing a flow of steam to be reheated serially through said re heater tube platens and then through said convection steam re heater.

6. In a steam generating unit, upright walls defining a vertically elongated furnace chamber and including steam generating tubes, means normally providing high temperature gases for the unit, means providing a convection section including a convection gas pass receiving gases from the upper part of the furnace chamber, a steam superheater including a convection section disposed within the convection gas pass and also including widely spaced pendent platens each having closely arranged superheater tubes disposed within the upper part of the furnace chamber, and a re heater including a convection section within the convection gas pass and a plurality of widely spaced pendent platens of closely arranged re heater tubes disposed in the upper part of the furnace chamber, the re heater platens alternating with and spaced from the platens of superheater tubes across the furnace chamber, each of said platens being formed by a series of single looped U-tubes having the legs of each tube substantially in contact throughout their length and aligned in the vertical plane of the corresponding platen, and a pair of steam inlet and outlet headers extending along the upper end of each platen and each connected to the corresponding leg of said U-tubes.

7. In a steam generating unit, walls defining a radiant heat absorption zone, said walls including steam generating tubes, furnace fuel burning means providing high temperature combustion gases for flow through the radiant heat zone, a steam heater including a convection section disposed within the gas flow beyond the radiant heat zone and having a radiant section including a continuous row of closely arranged tubes extending along a wall of the radiant heat zone and disposed inwardly of and in a vertical plane parallel to a row of steam generating tubes of that zone, tying means extending between and holding said steam heating tubes in inwardly spaced relation to said last named generating tubes and permitting relative vertical movement therebetween, and a gas-tight sheet metal casing fixedly and closely related to the row of steam generating tubes and disposed on the side of the

11

last mentioned row opposite the tubes of the radiant section of the steam heater.
